UNITED STATES PATENT OFFICE.

OSWALD S. PULLIAM, OF PITTSBURG, PENNSYLVANIA.

CAR-WHEEL.

No. 899,680.

Specification of Letters Patent. Patented Sept. 29, 1908.

Application filed October 11, 1907. Serial No. 396,878.

To all whom it may concern:

Be it known that I, OSWALD S. PULLIAM, of Pittsburg, in the county of Allegheny and State of Pennsylvania, have invented certain 5 new and useful Improvements in Car-Wheels, of which the following is a specification.

My invention relates to car-wheels and more particularly to steel-tired wheels.

In the accompanying drawing, which illustrates applications of my invention, Figure 1 is a cross sectional view of a car-wheel flask and steel-tired wheel located therein; Fig. 2 a similar view of my wheel showing position of wheel-center; Fig. 3 a sectional view of 15 finished wheel taken on line 3—3 of Fig. 4; Fig. 4 a broken plan; and Fig. 5, a broken plan of a modified form of wheel-center.

Referring to the drawing, 1 designates a steel-tire of the usual and well known form 20 inclosing a wheel-center. The wheel-center as illustrated and as preferred is made of cast-metal and comprises a hub-portion 2 and a plurality or series of radially extending members or pieces 3. These members 3 may 25 be in the form shown by Fig. 3 or in the form of spokes as shown by Fig. 5. The members 3 are formed integral with the hub 2 and are each formed on its outer end with a head 4. In addition to the head 4 each member is 30 formed with one or more waved or corrugated portions 5; the number, shape and depth of the corrugations may be varied.

In the drawing, I have illustrated the preferred method of making my car-wheels. 35 That is to say, Fig. 1 shows a flask 6 of the usual style employed in making car-wheels with the steel-tire embedded in the molding sand. The mold-cavity for the wheel-center is formed within the steel-tire, or if desired 40 instead of employing a steel-tire for a chill another form of chill may be used. The mold-cavity in addition to being formed to produce the hub and the radial members, is formed to produce the waved or corrugated 45 portions in said radial members of the wheel-center. The metal to form the wheel-center is poured into the mold-cavity against the steel-tire or other form of chill and assumes the position shown by Fig. 1. After pour- 50 ing, though, the wheel-center contracts some-

what, causing the periphery of the wheel-center to draw away a slight distance from the steel-tire into the position as illustrated by Fig. 2. To overcome this contraction of the wheel-center and to force the periphery 55 tightly against the tire the corrugated or waved portions are subjected to sufficient pressure to force the center against the tire as shown by Fig. 3. The pressure tends to straighten the corrugated portions, said cor- 60 rugations being of less depth after being pressed than before the pressure was applied.

In the form of Fig. 5, the corrugated portions of the spokes, after contraction as above described, are bent or straightened by 65 means of suitable tools. The inner surface of the tire is preferably provided with a series of nibs 7 against which the wheel-center is poured.

What I claim is:

1. A steel-tired car-wheel having a cast-metal wheel-center comprising a hub-portion and a plurality of radially extending segmental members formed integral with the hub-portion, each of said members formed 75 with a waved or corrugated portion and a tire-contracting-member.

2. A car-wheel having a metallic tire, and a separate wheel-center comprising a hub-portion and a plurality of radially extending 80 segmental members formed integral with the hub-portion, each of said members formed with a waved or corrugated portion.

3. A car-wheel having a metallic tire, and a separate wheel-center comprising a hub- 85 portion and a plurality of radially extending segmental members formed integral with the hub portion, each of said members formed with a waved or corrugated portion and a tire-contacting-member.

4. The method of making car-wheels which consists in casting a wheel-center with waved or corrugated radially extending members within a steel-tire, and then after the contraction of the wheel-center subjecting the 95 corrugated portions to sufficient pressure to cause the periphery of the wheel-center to come into contact with the tire.

5. The method of making car-wheels which consists in casting a wheel-center with 100

waved or corrugated radially extending members within a chill, placing the wheel-center within a metallic-tire and then subjecting the corrugated portions of the wheel-center to sufficient pressure to cause the periphery of the wheel-center to come into contact with the tire.

In testimony whereof I affix my signature in presence of two witnesses.

OSWALD S. PULLIAM.
